(57) **CLAIM**

I claim the ornamental design for a cosmetics case, as shown and described.

DESCRIPTION

FIG. 1 is a perspective view as seen from the front and top side of a cosmetics case in a closed position showing the new design.

FIG. 2 is a front elevational view thereof. The rear elevational view is identical to the front view.

FIG. 3 is a left side elevational view thereof. The right side elevational view is identical to the left side view.

FIG. 4 is a top view thereof.

FIG. 5 is a bottom view thereof; and,

FIG. 6 is a perspective view as seen from the front and top side of a cosmetics case in an open, stacked position showing the new design.

Specific features shown in broken lines do not form any part of or otherwise limit the claimed design.
